UNITED STATES PATENT OFFICE.

STACY B. HASELTINE, OF CHICAGO, ILLINOIS, ASSIGNOR TO WILLIAM H. MINER, OF CHICAGO, ILLINOIS.

DRAFT-YOKE FOR RAILWAY-CAR DRAFT-RIGGING.

1,130,692.

Specification of Letters Patent.

Patented Mar. 2, 1915.

Application filed August 4, 1913. Serial No. 782,756.

To all whom it may concern:

Be it known that I, STACY B. HASELTINE, a citizen of the United States, residing at Chicago, in the county of Cook and State of Illinois, have invented a certain new and useful Improvement in Draft-Yokes for Railway-Car Draft-Rigging, of which the following is a full, clear, concise, and exact description, reference being had to the accompanying drawings, forming a part of this specification.

My invention relates to improvements in draft yokes for railway car draft rigging.

The object of my invention is to provide a simple draft yoke so constructed as to permit the ready insertion and removal of the draw bar, and one in which the connecting means between the same may be reached and handled from the front end of the car.

In the drawings forming a part of this specification—Figure 1 is a perspective view of a draft yoke and draw bar, the rear end thereof only being shown, embodying my invention; Fig. 2 is a vertical longitudinal section through the forward end of the draft yoke and the rear end of the draw bar; Fig. 3 is a vertical longitudinal section through the rear part of the draft yoke; Fig. 4 is a detail showing in perspective one side of the yoke head, the forward end of the upper member of the yoke, a part of the same being broken away along the central longitudinal line thereof, and showing the forward end of the lower member of said yoke and the taper key, the said lower member being broken away to show the depending flange from said lower member of the yoke; Fig. 5 is a perspective view showing in detail the rear end of the yoke; and Fig. 6 is a perspective view of the taper key.

In the drawings 7 represents the shank of the draw bar, 8 the butt thereof, 9, 9 oppositely arranged shoulders with which said draw bar is provided, 10 the draft yoke, the said draft yoke having an upper limb 11, a lower limb 12, a rear member 13 dependent from the upper limb 11, and preferably integral therewith. The said upper limb is forwardly provided with a gib 14 adapted to engage the upper shoulder 9 of the draw bar. The said upper member is also provided at its forward end with lateral depending flanges or plates 15, 15, joined together at the bottom and constituting a band

to surround the draw-bar, and forming with the said upper limb 11 and the lower limb 12 of the yoke a box-like hollow head 16 to receive the butt 8 of the draw bar. The lower limb 12 is forwardly provided with a transverse lug or shoulder 40 adapted to engage the lower shoulder 9 of the butt of the draw bar, and is also provided with a depending transverse lug or flange 17, preferably integral with the said limb 12, and preferably provided at either edge of said limb with reinforcing preferably integral flanges 18, 18. In preferable construction the said depending flange or lug 17 is positioned substantially at a point in the length of said lower limb 12 coincident with the rear face 19 of the butt 8 of the draw bar. The said lateral flanges 15, 15 are downwardly extended at either side of the lower limb 12 of the yoke, and at their lower ends are joined by a transverse preferably integral plate 20 suitably removed from the lower limb 12 to form a space or recess 21 to receive the key 22. The said transverse plate 20 is in preferable construction longitudinally beveled on a line rearwardly converging toward the lower limb 12 of the yoke.

In preferable construction the key 22 is rearwardly tapered, the under-face 23 thereof being suitably beveled to engage against the beveled face of the said transverse member 20. The said key 22 is preferably provided on its under surface with a shoulder 24, which, when the key is in position within the recess 21, is sufficiently removed from the forward edge 25 of the transverse plate 20 to permit the insertion of means to remove said key 22 from the recess 21, as for instance a pinch-bar, should the same be required. The upper face 26 of said key is adapted to engage against the lower face 27 of the lower limb 12 of the yoke in front of the dependent flange 17 from said lower limb. The said key 22 is provided with a perforation 28 adapted to receive therethrough a bolt 29, the said bolt passing through a registering perforation 30 in the said dependent flange 17, the said bolt being provided with a head 31 engaging against the rear face of said flange, and at its forward end being provided with a nut 32 by means of which the key 22 may be rearwardly forced into the recess 21 to lift the lower limb of the yoke and draw bar into

position in the manner hereinafter described. The lower limb 12 of the yoke is detachable from the said yoke, and is rearwardly provided with means to engage the same to the connecting member 13 of said yoke.

- I prefer to employ the means shown in the drawings and described as follows:— The said connecting member 13 is provided at its lower end with a rearwardly extending transverse lug 33 adapted to engage within the transverse groove 34 with which the rear end of said lower limb is provided. I prefer to form said groove by providing the rear end of said lower limb 12 with an upturned preferably integral portion 35, having at its upper end a forwardly extended flange 36. In preferable construction the rear face of the connecting member 13 is provided with lateral reinforcing flanges 37, 37, and the rear end of the lower limb 12 is preferably provided with the reinforcing flange 38. It will be understood that the pocket 39 within the draft yoke is adapted to receive a draft gear therein.
- It will be apparent that on rearward movement of the draw bar the butt thereof may slide rearwardly within the yoke, and on forward movement will draw the yoke forwardly by reason of the interengagement of the gibs of the yoke with the shoulders of the draw bar. To remove the draw bar from the yoke when the draft rigging of which the same are a part are mounted between the draft sills of a car the bolt 29 is removed, and the key 22 withdrawn forwardly from the hollow head, dropping the forward end of the yoke to the lower portion of the hollow opening of the yoke head, whereupon the upper shoulder 9 of the draw bar will disengage from the upper gib 14 of the yoke, and sufficient space will be provided between the upper gib and the lower gib 40 of the detachable limb of the yoke to permit the draw bar to be drawn forwardly and removed. Meanwhile a draft gear within the yoke may remain therein until the draw bar is replaced, as may be desired, or if it is desired to remove the draft gear from the yoke the same may be done by moving the detachable limb of the yoke rearwardly, and dropping the same after the key 22 and bolt 29 have been removed. On replacing the draw bar within the yoke the same is passed through the forward opening of the yoke between the gibs thereof while the detachable member is resting within the hollow head of the upper member, and thereupon the taper key 22 is inserted underneath the forward portion of the detachable limb, and between it and the inner lower face of the hollow head, and driven into position, thus lifting the draw bar into position with the shoulders thereof in engagement back of the gibs of the limbs of the yoke, and the taper key secured in po-

sition by means of the bolt passing therethrough.

I claim:—

1. In railway car draft rigging, the combination with a draw bar, of a draft yoke comprising a limb having an integral band surrounding the draw bar and a detachable limb, of a key to secure one end of said detachable limb within said band.

2. In railway car draft rigging, the combination with a draw bar, of a draft yoke having a pair of limbs, one of said limbs being provided with an integral band to receive the draw bar and a detachable limb, of a key to secure one end of said detachable limb within said band, said key being tapered to wedge said detachable limb against the draw bar.

3. In a railway car draft rigging, in combination, a draw bar, a key, and a draft yoke having a pair of limbs, one of said limbs being provided with a band to surround the draw-bar, the other limb being detachable, and said key being adapted to be received in a forward opening of said band to hold the detachable limb to the draw bar.

4. In a draft rigging for railway cars, in combination, a draw bar, a key, and a draft yoke comprising a limb having a band integral therewith to surround the draw bar and a detachable limb, the said detachable limb being received within said band, and said key engaging between said limb and an internal face of the band.

5. In a draft rigging for railway cars, in combination, a draw bar, a key, and a draft yoke comprising a limb having a band integral therewith and a detachable limb, said detachable limb being provided at its rear end with means for engaging the other limb, and being adapted at its other end to enter the band and engage the draw bar, the said key securing the detachable limb within the band.

6. In a draft rigging for railway cars, in combination, a draw bar and a draft yoke comprising a limb having an integral band surrounding the draw bar, and a detachable limb engaging said first mentioned limb at its one end, and adapted to be secured within the band at its other end.

7. In a draft rigging for railway cars, in combination, a draw bar, a key, and a draft yoke comprising a limb having a band integral therewith surrounding the draw bar and a detachable limb, said detachable limb having integral means to engage said first mentioned limb at one end and entering the band at the other end, said key being adapted to hold the detachable limb in engagement with the draw bar within the said band.

8. In a draft rigging for railway cars, a draw bar, a key and a draft yoke, the draft yoke comprising a limb having a hollow

head surrounding the draw bar and a detachable limb entering said head, the said key engaging the detachable limb within the head, and being removable through the forward opening of said head.

9. In a draft rigging for railway cars, in combination, a draw bar, a key and a pair of yoke limbs, one of said limbs being provided with an integral band surrounding the 10 draw bar, the other limb engaging the first mentioned limb at the rear end and engaging within the band at its other end, the key being received within the band, said last mentioned limb having a flange to engage 15 means to secure the key within the band.

10. In a draft rigging for railway cars, a draw bar, a key, a bolt and a draft yoke, the draft yoke comprising a limb having a hollow head surrounding the draw bar and a 20 detachable limb, said limbs having means for co-engagement at their rear ends, the detachable limb entering the hollow head at its forward end, the key engaging between the hollow head and the detachable 25 limb within the hollow head, the detachable limb having a dependent flange, and the bolt passing through the key and said flange.

11. In a draft rigging for railway cars, a draw bar having opposed shoulders, a key 30 and a draft yoke, the draft yoke comprising a limb having an integral band surrounding the draw bar and a detachable limb entering said band, both of said limbs having gibs 35 engaging the shoulders of the draw bar, the key entering the forward opening of said band and wedging the detachable limb against the draw bar.

12. In a draft rigging for railway cars, in combination, a draw bar, a draft yoke comprising a limb forwardly provided with an 40 integral band surrounding the draw bar, and a detachable limb receivable within the band, and means to secure the detachable limb within the band, said first mentioned 45 limb being rearwardly provided with a transverse lug, and the detachable limb having a transverse groove within which the said lug engages.

13. In a draft rigging for railway cars, a 50 draw bar and a draft yoke comprising a limb having an integral band surrounding the draw bar at one end and an upright member at the other end, and a detachable limb engaging against the upright member 55 at one end and passing within the band at its other end, in combination with means for

securing the detachable limb within the band.

14. In a draft rigging for railway cars, a draw bar and a draft yoke comprising a limb having an integral band surrounding 60 the draw bar at one end and an upright member at the other end, and a detachable limb engaging against the upright member at one end and passing within the band at its other end, in combination with means for 65 securing the detachable limb within the band, said means being forwardly removable from the opening of said band.

15. In a draft rigging for railway cars, in combination, a draw-bar, a key, and a draft 70 yoke, the draft yoke comprising a pair of limbs, one of said limbs having an integral band to surround the draw-bar, the other limb entering said band and having integral means to secure it at its other end to the 75 first mentioned limb, the key being adapted to hold the last mentioned limb within the band.

16. A draft yoke for railway draft rigging comprising two members one of which 80 is provided with a band at the forward end thereof adapted to receive a draw bar butt, the other member being detachably connected to the first named member at the rear thereof, and means for releasably holding the front end of the last named member 85 in operative position against said band.

17. A coupler yoke comprising a plurality of arms, each of said arms having a shoulder adapted to receive pulling strains from a 90 coupler butt, said arms being connected at one end by a removable member, and by an interlocking engagement with each other at their other ends, said arms being separable by withdrawal of the removable member and 95 by an initial longitudinal movement of the lower yoke arm.

18. A coupler yoke consisting of a body portion, a longitudinally extending lower arm having at one end a longitudinally disengageable interlocking connection with the body portion, and a separate member securing the two parts together at their other ends, the lower arm being disengaged from the body portion by an initial longitudinal 100 movement without disturbing the draft rigging.
